Inventor:

Conrad J. Dorff.

by Robert Burns

Attorney,

UNITED STATES PATENT OFFICE.

CONRAD J. DORFF, OF CHICAGO, ILLINOIS, ASSIGNOR TO THE HARVARD ELECTRIC COMPANY, OF CHICAGO, ILLINOIS, A CORPORATION OF ILLINOIS.

FUSE FOR ELECTRIC CIRCUITS.

949,296.

Specification of Letters Patent. Patented Feb. 15, 1910.

Application filed October 28, 1907. Serial No. 399,554.

To all whom it may concern:

Be it known that I, CONRAD J. DORFF, a citizen of the United States of America, and a resident of Chicago, in the county of Cook and State of Illinois, have invented certain new and useful Improvements in Fuses for Electric Circuits, of which the following is a specification.

This invention relates to that type of fuses for electric circuits in which a supporting strip of insulating material is provided at its respective ends with terminal bindings, which in turn are connected together by an attenuated wire of lead or like material cemented to the insulating strip aforesaid and adapted to fuse under an excess of current and open the circuit; and the object of the present improvement is to provide a simple and efficient structural arrangement of parts in a fuse of the type above mentioned, whereby the attenuated and fragile fuse wire is protected from abrasion and fracture during handling, shipment and use, all as will hereinafter more fully appear.

In the accompanying drawings:—Figure 1 is a front elevation of a fuse embodying the present invention. Fig. 2 is a longitudinal section at line $x-x$ Fig. 1. Fig. 3 is a transverse section at line $x'-x'$ Fig. 1.

Similar numerals of reference indicate like parts in the different views.

Referring to the drawings:—1 represents the supporting strip of insulating material, and usually formed of two sheets of mica placed one on the other and bound together at their ends by wrappings 2 of thin sheet copper or the like; such wrappings constituting the respective terminals of the fuse as usual in the present type of such devices.

3 is the usual fuse wire of lead or like material having a low conductive capacity, and which extends between the terminals 2, aforesaid.

The present invention involves the provision of a longitudinal channel 4 in the insulating supporting strip 1, and extending from one to the other terminal or wrapping 2, for the reception of the fuse wire 3, which may be cemented therein by a suitable varnish or other like readily fusible and non-conducting adhesive.

In the preferred form of the present improvement shown in the drawings, the chan-

nel 4 is formed by punching an elongated slot in one of the sheets of mica comprising the supporting strip 1, the companion sheet being left imperforate to form a backing for said slot and form the channel 4 aforesaid.

Another part of the present improvement consists in depressing a portion of the wrappings 2 into the channel 4 to cause a contact with the respective ends of the fuse wire 3, and at the same time form shallow depressions 5 to receive the small masses 6 of solder by which a positive conductive connection is effected between the respective ends of the fuse wire and said terminals or wrappings.

Having thus fully described my said invention, what I claim as new and desire to secure by Letters Patent, is:—

1. A fuse for electric circuits, comprising a thin rectangular and flexible strip of insulating material formed with a shallow longitudinal channel, sheet metal terminals wrapped upon the ends of said strip, and a longitudinal fuse wire arranged in said channel and electrically connected at its ends to said terminals, said channel protecting the fuse wire from abrasion in handling the fuse.

2. A fuse for electric circuits, comprising a supporting strip of insulating material, sheet metal terminals on the ends of said strip, and a fuse wire extending between the terminals, the said strip having a longitudinal channel for the reception of said fuse wire and the said terminals having depressed portions fitting said channels and adapted to receive the small masses of solder by which the terminals are electrically connected to the fuse wire.

3. A fuse for electric circuits, comprising a supporting strip of insulating material, sheet metal terminals on the ends of said strip, and a fuse wire extending between the terminals, the said strip being formed of two sheets, one of which is formed with an elongated slot to constitute a receiving channel for the fuse wire.

Signed at Chicago, Illinois, this 22nd day of October, 1907.

CONRAD J. DORFF.
